PICKER STICK STRAP LUG

Alvin N. Ayers, Asheville, N. C., and Liday Elury
Hamilton, Sr., Atlanta, Ga.; said Ayers assign-
or to said Hamilton

Application August 23, 1946, Serial No. 692,682

1 Claim. (Cl. 139—154)

1

This invention relates to picker stick strap lugs for looms.

An object of this invention is to provide an improved lug or holder for the strap engaging about the picker stick which is so constructed as to eliminate wear on the strap and on the lug or holder so that the latter will last for an indefinite period.

Another object of this invention is to provide an improved lug or holder for a picker stick which can be made out of either wood, metal, such as an aluminum alloy or the like, which due to its improved construction will effect an economy in the operation of the loom.

A further object of this invention is to provide an improved lug or holder for a picker stick which is so constructed that it cannot shift laterally or become twisted on the picker stick in the event the clamping bolt should become loose.

With the above and other objects in view, our invention consists in the arrangement, combination and details of construction disclosed in the drawings and specification, and then more particularly pointed out in the appended claim.

In the drawings,

Figure 1 is a detail side elevation, partly broken away and in section, of a picker stick strap lug constructed according to an embodiment of this invention,

Figure 2 is a detail front elevation of the device partly broken away and in section,

Figure 3 is a sectional view taken on the line 3—3 of Figure 1,

Figure 4 is a fragmentary sectional view taken on the line 4—4 of Figure 1,

Figure 5 is a detail side elevation, partly broken away and in section, of a modified form of this invention,

Figure 6 is a detail front elevation of the device shown in Figure 5,

Figure 7 is a detail side elevation, partly in section, of another modification of this invention,

Figure 8 is a detail front elevation of the device shown in Figure 7,

Figure 9 is a fragmentary sectional view taken on the line 9—9 of Figure 7,

Figure 10 is a detail side elevation of a further modification of this invention,

Figure 11 is a detail front elevation of the device shown in Figure 10,

Figure 12 is a detail side elevation of a further modification of this invention,

Figure 13 is a fragmentary front elevation of the lower portion of the device shown in Figure 12.

Referring to the drawings, the numeral 15 des-

2

ignates generally a picker stick of conventional construction which has associated therewith a strap 16 connected to a conventional operator for rocking the picker stick. A lug or strap holder 17 generally designated as 17 is interposed between the bight 18 of the strap 16 and the adjacent edge of the picker stick 15. The lug or holder 17 includes an elongated body 19 which is formed on the rear side thereof with a longitudinally extending channel 20, thereby forming lengthwise flanges 21 which are adapted to engage on the opposite sides of the picker stick 15. In this manner the lug or holder 17 is held against lateral shifting or twisting on the picker stick.

15 The lug or holder 17 also includes at its upper end an outwardly projecting lug 22. The lug 22 is formed with an outwardly and upwardly inclined inner side 23 which, as shown in Figure 2, is rounded so as to provide a smooth surface 20 for contact with the strap 16 in the event the strap moves upwardly on the holder. The lug 22 prevents the strap 16 from riding upwardly and off of the body 19 of the holder, and the inclination 25 of the inner side of the lug 22 provides for the free sliding movement downwardly of the strap 20 for engagement with the body 19. In this manner the strap 16 will always be disposed in the same position on the picker stick so as to provide for the same arcuate or rocking movement 30 of the picker stick.

The body 19 at its lower end is formed with a pair of laterally and oppositely extending lugs or ears 24 which provide a means whereby the strap 16 is held in the space between the lug 22 35 and the lugs or ears 24. The body 19 also includes a reduced thickness lower or shank portion 25 which at its upper end is formed with a channel 26 extending transversely thereacross for receiving the bight 27 of a U-bolt 28. The opposite legs of the U-bolt 28 are adapted to straddle the sides of the picker stick 15 and a clamping or pressure plate 29 engages the inner edge of the picker stick 15 and is held in clamping position by a pair of nuts 30 threaded onto the legs 40 of the U-bolt 28.

Referring now to Figures 5 and 6, there is disclosed another modified form of this invention which includes a body 31 similar to the body 19, having extending therefrom a lug 32 similar to 45 the lug 17. In the present instance, the lug 32 extending from an intermediate point in the length of the body 31 and the body 31 includes an upper extension 33 which is engaged by the U-bolt 34.

50 The body 31 is also formed with a longitudinal-

ly extending channel 35 similar to the channel 20 and at the lower end the body 31 is formed with a pair of integral laterally extending ears or lugs 36. In this manner the strap holder is held from a point above the strap rather than from a point below the strap, as shown in Figure 1.

Referring now to Figures 7, 8, and 9 there is disclosed another modification of this invention. A holder generally designated as 37 includes an elongated body 38 formed with a lengthwise extending channel 39 on its inner edge for receiving the outer edge of the picker stick 15. The body 38 is rounded in transverse section as indicated at 40 in Figure 9 so that the body 38 will not chafe or otherwise injure the bight 18 of the picker stick strap 16. The body 38 at its upper end is formed with an outwardly projecting lug 41 which is formed with an upwardly and outwardly inclined lower side 42 rounded in transverse section.

The body 38 at a point spaced downwardly from the lug 41 has projecting therefrom a second lug 43. The strap 16 is adapted to loosely engage between the two lugs 41 and 43.

The body 38 projects below the lower lug 43 and the body is formed with a channel 44 within which the bight and a portion of the parallel legs of a U-bolt 45 are adapted to be snugly received. The U-bolt 45 also includes a clamping plate 46 held in clamping position by a pair of nuts 47 threaded onto the U-bolt 45.

Referring now to Figures 10 and 11 there is disclosed another modification of this invention which is the reverse of the form shown in Figures 7, 8, and 9. An elongated body 48 is formed with a lengthwise extending channel 49 within which the outer edge of the picker stick is received. The body 48 at a point between the upper and lower ends thereof has projecting therefrom an upper lug 50 which is formed with an upwardly and outwardly inclined lower side 52. The lower side 52 is also formed with a convex surface as shown in Figure 11. The lower lug 53 is formed integral with the body 48 at its lower end and projecting from the body 48 at a point spaced downwardly from the lug 50 so that the strap may be loosely engaged between the two lugs 50 and 53. The body 48 is also formed with a channel or groove 54 which is above the upper lug 50 for snugly receiving the bight and outer portions of the parallel legs of the clamping U-bolt.

Referring now to Figures 12 and 13, there is disclosed a lug or holder 55 which includes an elongated body 56 formed with a convex or rounded outer side. The body 56 is also formed with a longitudinal channel 57 on its inner edge within which the outer edge of the picker stick 15 is adapted to be snugly received. The body 56 at its upper end has extending therefrom an integral lug 58 which is formed with an upward-

ly and outwardly inclined lower side 59. The lower side 59 is of convex configuration in transverse section. The body 56 has extending therefrom a reduced thickness lower portion 60 on which a lower lug member generally designated as 61 is adapted to be engaged.

The lug member 61 includes an elongated bar 62 which has formed integral with the upper end thereof a right angularly disposed lug forming head 63 which provides a pair of oppositely projecting lugs or arms 64. The head 63 is braced by means of right angularly disposed bracing webs 65 and 66. The lower end of the bar 62 is formed with a transversely disposed groove 67 within which the bight of the U-bolt is adapted to be received so that when this U-bolt is tightened the bar 61 will be tightly clamped to the extension 60 and this extension with the body 66 will be tightly clamped to the picker stick.

With a picker stick strap lug or holder constructed according to an embodiment of this invention, the holder will have a longer useful life than holders at present in use, particularly the holders which are made out of laminated leather or the like. This holder may be made out of any suitable material such as wood, metal or the like, and under practical experiments this lug has been found to out last lugs or holders which are at present available and in use.

We do not mean to confine ourselves to the exact details of construction herein disclosed but claim all variations falling within the purview of the appended claim.

What we claim is:

35 A picker stick holder comprising an elongated body formed in one side thereof with a lengthwise channel within which the stick is adapted to engage, a lug projecting from said body oppositely from said channel and a pair of laterally 40 projecting lugs carried by said body in spaced relation to said first lug and disposed between the ends of said body, the space between said first named lug and said pair of lugs being adapted to receive the lug strap, said body having a groove 45 adjacent said pair of lugs within which a U clamp is adapted to engage.
